UNITED STATES PATENT OFFICE.

LINNAEUS E. BAKER, OF FORT WAYNE, INDIANA, ASSIGNOR TO WAYNE OIL TANK & PUMP CO., A CORPORATION OF INDIANA.

HOUSING FOR DISPENSING APPARATUS.

1,178,986.

Specification of Letters Patent. Patented Apr. 11, 1916.

Application filed April 12, 1915. Serial No. 20,671.

To all whom it may concern:

Be it known that I, LINNAEUS E. BAKER, a citizen of the United States of America, and resident of Fort Wayne, in the county of Allen and State of Indiana, have invented certain new and useful Improvements in Housings for Dispensing Apparatus, of which the following is a specification.

This invention relates to improvements in dispensing apparatus, and more particularly to housing for inclosing apparatus of various kinds that are installed ordinarily out of doors at places exposed to weather and pillage.

The objects of this invention are:—First, to so construct a housing that its contained operating mechanism may be completely incased and secured from the weather and from tampering by unauthorized persons; second, to provide a movable section of the housing so arranged that the operating mechanism of the dispensing apparatus contained within the housing may be completely exposed and rendered accessible for operation; third, to so arrange the movable section of the housing as to retain compactness of the complete apparatus when the movable section is in its open position; fourth, to so mount the movable section of the housing that it may be opened or closed with but little physical effort; and fifth, to provide means of illumination for the operating mechanism contained in the space between the dome and pedestal.

The above objects are accomplished by the construction illustrated in the accompanying drawings in which: Figure 1 is an elevation showing the exterior of the device, 40 a portion being cut away to expose an interior detail; Fig. 2 is a vertical section of Fig. 1 on a plane at right angles thereto; Fig. 3 is a detail view showing a portion of the housing and with the movable section 45 thereof in open position exposing the operating parts of the contained dispensing apparatus; Fig. 4 is an abbreviated vertical section of the housing with the movable section thereof in closed position, the dispens- 50 ing apparatus being omitted; Fig. 5 is a detail view in cross-section showing one of the guide-blocks for the movable section; Fig. 6 is a transverse section of the device at a point above the pedestal and showing por- 55 tions cut away; and Fig. 7 is a detail view

showing a vertical section through the upper part of the pedestal.

Similar characters of reference indicate corresponding parts throughout the several views and referring now to the same:

The housing is composed of three principal parts, (1) constituting the pedestal, (2) the dome, and (3) the movable section.

The pedestal (1) is of cylindrical form and is shown with a series of integral, vertical columns (4). Upon the outermost part of each of the columns is a projecting rib (5), the ribs serving as guides for the movable section (3) as it is being shifted telescopically over the pedestal. The dome (2) is supported rigidly upon tubular posts (6) that are seated at their lower ends upon brackets (7) that project within the pedestal, and are fixed at their upper ends in brackets (8) projecting within the dome. 75 The dome may be of any desired form, as per example: An extension (9) with a superimposed globe (10) may be provided for ornamentation and illumination. The posts (6) have threaded connection at their tops in the brackets (8) respectively, and in the lower end of each post is a threaded plug (15) that rests upon the corresponding bracket (7) and is secured thereto by means of a bolt (16). The threaded plugs (15) 80 admit of being turned so that the corresponding tubular posts may be adjustably raised or lowered as occasion may require to plumb the dome. The movable section (3) consists of a cylinder telescopically ar- 90 ranged over the pedestal (1) and adapted to fit at its upper end within the chine (11) of the dome, when in its uppermost position. The movable section (3) is supported by idlers (12) that are trained over 95 idlers (13) that are supported in the dome and that have weights (14) attached to their respective opposite ends and are adapted to move within the corresponding tubular posts (6). The weights are proportioned 100 as to heft so as to counterbalance the movable section. Thus the movable section will remain in either closed or open position by inertia. The function of the movable section is, when in uppermost position, to inclose the space between the pedestal and the dome, or, when in lowermost position, to leave the space between the pedestal and dome entirely unobstructed by itself.

Upon the inner side at the top of the 110

movable section (3) is fixed a projecting hasp (17) that is adapted to become engaged by the bolt (18) of a lock (19) located in the dome, so that the movable section may be locked in its closed position. The cylindrical movable section (3) is guided over the pedestal by the ribs (5) and also by guides (20) that are secured to the movable section at its interior upper edge and which are shaped to conform respectively with the adjacent surfaces of the corresponding tubular posts upon which they are adapted to slide as the movable section is raised or lowered. Each of the guides has an eyebolt (21) that affords the means of connection with the corresponding chain or cable (12). The pedestal (1) has in its wall near the lower end thereof a removable door (22) which, when removed, admits of access to the interior of the pedestal. At the top of the pedestal is a flange (23) that affords a seat for the cylinder-head (24) of the dispensing apparatus that is inclosed within the housing, the cylinder-head having a flange (25) that extends over the flange (23) on the pedestal and rests thereupon. Bolts (26) serve to secure the two flanges together. The tubular posts (6) are placed so as to extend partially within two opposite columns (4) of the pedestal, and extend through the flange (25) of the cylinder-head, and are thereby rigidly held in upright position. The cylinder-head (24) while forming a part of the dispensing apparatus that is contained within the housing, serves also as a closure for the top of the pedestal. Therefore, the cylinder (27), that is attached to the cylinder-head and supported thereby is contained within the pedestal and concealed from view. The operating mechanism (28) of the dispensing apparatus is arranged upon the cylinder-head and extends upwardly within the space between the pedestal and the dome so that the same may be exposed and made accessible for operation when the movable section is in open position.

The dispensing apparatus in this instance is for handling liquids such as gasoline, oils, etc., and consists of the cylinder (27) containing a plunger (29) and having an inlet (30) for liquid, the cylinder being attached to the head (24); and the operating mechanism (28) that is constructed to actuate the plunger, a crank (31) being provided for the purpose of manipulating the same. The dispensing apparatus herein shown is also provided with two discharge pipes (32) and (33) respectively; the former extends upwardly to a point approximately within the dome and has in connection therewith a flexible discharge member (34), and the latter being horizontally disposed and being adapted to be swung upon its connection

with a vertical outlet pipe (35) that has communication through the cylinder-head with the pump-cylinder. The discharge pipe (33) has at its outer extremity a faucet (36) and is proportioned as to length so that when swung to innermost position it will be encompassed by the movable section, when the latter is closed, and when swung to its outermost position will overhang the same. In some instances it is desirable to extend the discharge pipe (32) upwardly through the dome so that its connection with the flexible discharge member (34) will be on the exterior of the housing as shown in Fig. 1.

Within the housing is an electrical conduit (37) that extends up through the dome to the lamp (38) that is located within the globe (10). The conduit is of the usual type containing wires for transmitting electric current. A feature of the invention is the arrangement of a lamp (39) within the dome for illuminating the operating mechanism of the dispensing apparatus and the preparation of the surface of the interior of the dome with a coating of white enamel or other light reflecting substance. The lamp (39) receives its current through a branch (40) of the conduit (37). The lamp (39) upon the top of the dome serves to illuminate the vicinity and attract attention to the location of the apparatus, while the lamp (39) within the dome, augmented by the reflection of the rays of the lamp by the interior surface of the dome throws light directly upon the operating mechanism that is located in the space between the dome and pedestal.

What I claim is:—

1. In housing for dispensing apparatus, a pedestal; a dome mounted above the pedestal leaving a space therebetween; and a movable section of less diameter than the dome and greater diameter than the pedestal and adapted to inclose the space between the dome and pedestal.

2. In housing for dispensing apparatus, a pedestal; a dome mounted above the pedestal leaving a space therebetween; and a section for closing the space between the pedestal and dome so proportioned as to be moved downwardly from the dome, and telescope the pedestal so as to expose the space.

3. In housing for dispensing apparatus, a pedestal having upon its exterior a series of guides; a dome mounted above the pedestal leaving a space therebetween; and a section for closing the space and being adapted to be moved downwardly upon the guides and expose the space.

4. In housing for dispensing apparatus, a pedestal; supporting posts extending upwardly from the pedestal; a dome fixed upon the posts at a point above the pedestal leaving a space therebetween; and a cylin-

drical section adapted to be moved downwardly over the pedestal and expose the space, or to be moved upwardly to the dome and inclose the space, accordingly as shifted from one position to the other.

5. In housing for dispensing apparatus, a hollow pedestal; tubular posts extending upwardly through the pedestal to a point above the top of the same; means at each end of the pedestal for supporting the posts; a dome fixed upon said posts at the tops thereof; and a cylindrical section closing the space between the pedestal and dome and being adapted to be moved downwardly over the pedestal and expose the space.

6. In housing for dispensing apparatus, a hollow pedestal adapted to contain a portion of a dispensing apparatus; a dome supported above the pedestal in fixed relation therewith, there being a space therebetween for another portion of the dispensing apparatus; and a cylindrical section adapted to inclose the apparatus within the space and being also adapted to be moved downwardly over the pedestal and expose the space and its contained apparatus.

7. In housing for dispensing apparatus, a hollow pedestal; a dome forming the top of the housing; posts mounted in the pedestal and supporting the dome in fixed relation therewith; and a movable section completely inclosed at its upper end by the top of the housing, its lower portion extending over the top of the pedestal and inclosing the space between the latter and dome, said section being adapted to be shifted downwardly from the dome and leave exposed the space between its top and the dome.

8. In housing for dispensing apparatus, a hollow pedestal; a dome forming the top of the housing; posts extending up through the pedestal and supporting the dome at a point above the pedestal leaving a space therebetween; means in fixed relation at the top of the pedestal for supporting the posts; means at the lower ends of the pedestal and posts for adjusting the latter; and a movable section the upper end of which is adapted to fit within the dome, and the lower portion of which is adapted to telescope the pedestal when the section is moved downwardly.

9. In housing for dispensing apparatus, a pedestal; a dome forming the top of the housing and mounted above the pedestal, there being a space between the dome and pedestal; a movable section adapted to inclose the space between the dome and pedestal; and means to counterbalance the movable section.

10. In a device of the class described, a housing having a pedestal and dome in fixed relation with each other with a space intervening therebetween, the pedestal and space being adapted to contain dispensing ap-

paratus, and a cylindrical section for inclosing the space and being so proportioned as to be inclosed at its upper end by the dome and to be moved downwardly over the pedestal and expose the space.

11. In housing for dispensing apparatus, a pedestal; tubular posts extending upwardly from the pedestal; a dome fixed upon the posts and supported thereby, there being a space between the pedestal and dome; weights movably arranged within the tubular posts; idlers supported under the dome adjacent the tops of the tubular posts respectively; and a vertically movable section for inclosing the space between the pedestal and dome; and cables connected respectively with the weights and extending over the corresponding idlers and having also connection with the movable section.

12. In a device of the class described, a housing having a pedestal and dome in fixed relation with each other and with an open space therebetween; tubular posts supporting the dome; a vertically movable section for inclosing the space; and weights having suitable connection with the movable section and extending within the tubular posts respectively.

13. In a device of the class described, a housing having a pedestal and dome with a space therebetween; a vertically movable section for inclosing the space between the pedestal and dome; and counterbalancing means for the movable section.

14. In apparatus of the class described, a housing having a fixed pedestal and dome with a space therebetween; a counterbalanced movable section for inclosing the space and for inclosing a dispensing apparatus within the housing which apparatus has a flanged-head adapted to rest upon the top of the pedestal and close the same.

15. In a housing for dispensing apparatus, a pedestal; parallel tubular posts extending upwardly from the pedestal; a dome fixed upon the tops of the posts; a cylindrical section for inclosing the space between the dome and pedestal formed so as to be inclosed at its top by the dome and slide downwardly over the pedestal when shifted to open position; and guides extending inwardly from the upper end of the section and having sliding relation with the posts.

16. In housing for dispensing apparatus, a pedestal, having upon its exterior vertically disposed ribs; parallel posts extending upwardly from the pedestal; a dome fixed upon the tops of the posts; and a movable section for inclosing the space between the pedestal and dome, the upper end of the section having guides that have sliding connections respectively with said posts, the section being held from rubbing contact with the surface proper of the pedestal by said ribs.

17. In housing for dispensing apparatus, a hollow pedestal for containing a portion of the dispensing apparatus; a dome forming the top of the housing and having fixed 5 relation with the pedestal there being a space between the same for the operating mechanism of the dispensing apparatus; a vertically movable section having telescopic relation with the pedestal and adapted to 10 inclose the operating mechanism within the space between the pedestal and dome and the dispensing apparatus having a flanged head fixed upon the top of the pedestal to support the apparatus and close the top of 15 the pedestal.

18. In apparatus of the class described, a housing having a pedestal and dome, there being a space intervening between the same for inclosing a dispensing apparatus and mechanism for operating the same, and 20 lighting means located within the dome adapted to shed light in the space between the pedestal and dome.

In testimony whereof I affix my signature, in presence of two witnesses.

LINNAEUS E. BAKER.
